(**) Term: **15 Years**

(21) Appl. No.: **29/530,317**

(57) **CLAIM**

(22) Filed: **Jun. 16, 2015**

The ornamental design for a tread portion of an automobile tire, as shown and described.

(30) **Foreign Application Priority Data**

Dec. 24, 2014 (JP) 2014-028877

DESCRIPTION

(51) **LOC (10) Cl.** **12-15**

FIG. 1 is a perspective view of the tread portion of an

(52) **U.S. Cl.**

automobile tire showing my new design;

USPC **D12/521**

FIG. 2 is a front view thereof;

(58) **Field of Classification Search**

FIG. 3 is a right side view thereof;

USPC D12/519-532, 551-567, 586-603, 145,

FIG. 4 is a left side view thereof;

D12/900, 901

FIG. 5 is a partial front view of the tread shown enlarged for

CPC B60C 1/0016; B60C 11/0302-11/0318;

clarity of illustration;

B60C 11/11-11/13; B60C 3/06; B60C

FIG. 6 is a sectional view taken in the direction defined by

9/17; B60C 2200/10

line 6-6 in FIG. 5; and,

See application file for complete search history.

FIG. 7 is a sectional view taken in the direction defined by

(56) **References Cited**

line 7-7 in FIG. 5.

U.S. PATENT DOCUMENTS

The broken lines illustrate portions of the sidewall, bead,

D606,926 S * 12/2009 Heinen D12/521
D708,564 S * 7/2014 Wang D12/521

and interior surface of a tire, and form no part of the claimed

design.
